UNITED STATES PATENT OFFICE.

JAMES J. WITKOWSKI, OF ALBION, NEW YORK.

BATTERY CONNECTER.

Application filed August 27, 1926. Serial No. 131,886.

This invention relates to terminals for connecting conducting wires to the posts of storage batteries as used on motor cars; and it consists in the novel construction and combination of the parts hereinafter fully described and claimed.

In the drawings, Figure 1 is a side view of a battery connector constructed according to this invention. Fig. 2 is a plan view of 10 the same. Fig. 3 is an end view of the connector.

The battery connectors mostly used have their clamping bolts arranged in positions in which their nuts are hard to get at on 15 motor cars. In carrying out this invention the clamping bolt is arranged parallel to the battery post, and the clamping members are arranged and constructed so that they can be operated by a slight movement of the 20 clamping nut at the top of the clamping bolt.

The clamping post 6 of the battery is the same as ordinarily used. The wire or conductor 7 is secured to a split sleeve 8 which 25 slips freely over the post 6, and has two clamping arms 5 projecting laterally from it, and arranged one on each side of its split or gap 9. These arms are thickest at their middle parts, and their sides are tapered 30 from their middle parts to their tops and bottoms.

A lower clamping member 10 and an upper clamping member 12 are provided, and are each channel-shaped in cross-section, their 35 sides 14 being tapered to correspond with the taper of the sides of the clamping arms. The faces of the sides 14 are convex, so that their middle parts bear hard on the sides of the arms.

40 The lower clamping member has a clamping bolt 15 which projects from it upwardly

through a hole 16 in the middle part of the top of the upper clamping member 12, and has a clamping nut 17 screwed on its projecting end portion. The lower part 18 of the bolt is smooth where it projects through the gap 9 between the clamping arms. The split sleeve 8 is caused to grip the post tightly when the clamping nut is screwed up a little, and as the clamping bolt is arranged parallel to the post and the axis of the sleeve, and with the nut at its upper part, the nut is very easy of access, and the connection can be made and broken with great facility as often as required. The 55 arms 5 are grooved so that they always clear the clamping bolt.

What I claim is:

1. A battery connector, comprising a split sleeve for engaging with the battery post, 60 said sleeve having two laterally projecting clamping arms provided with tapering sides, an upper clamping member and a lower clamping member engaging with the said sides, the said upper member having a bolt 65 hole, a bolt which projects from the lower clamping member parallel to the axis of the said sleeve and through the said bolt hole, and a clamping nut screwed on the projecting end portion of the said bolt.

2. A battery connector as set forth in 70 claim 1, the said clamping arms being thickest at their middle parts and tapered from their middle parts to their tops and bottoms.

3. A battery connector as set forth in 75 claim 1, the sides of the said clamping members having convex faces which bear on the sides of the clamping arms.

In testimony whereof I have affixed my 80 signature.

JAMES J. WITKOWSKI.
